APPARATUS FOR REDUCING TUBES

Gustav Asbeck, Dusseldorf, Germany

Application May 10, 1934, Serial No. 724,968. Renewed January 7, 1938. In Germany November 11, 1933

1 Claim. (Cl. 80—11)

The passage of tubes through reducing rolls has hitherto resulted in the formation of corners or ridges in the interior of the tubes, which is extremely undesirable. The cross-section of a tube of this kind is illustrated by way of example in Figure 1 of the drawing. These corners or ridges are found as a result of the irregular increases in the thickness of the wall of the tube arising from the effect on the tube of the spaces or clearances between the flanks of the adjacent rolls constituting one set of reducing rolls. It is well known that a tube spreads out more or becomes thicker in the region of the said clearances than at the crown of the grooves in the rolls. This effect is accentuated because, for technical reasons the grooves of the reducing rolls must be of semi-oval shape with the major axis of the oval parallel to the axis of the roll.

In the usual method of reducing tubes in known rolling mills in which the planes of revolution of the successive sets of reducing rolls are displaced relatively or staggered with the object of rolling down the external ridges or fins resulting from the passage of the tube through a preceding set of reducing rolls, the planes of revolution of both the even numbered and of the odd numbered sets of reducing rolls are situated in the same angular positions. That is to say, whilst all the even numbered sets have the planes of revolution of their rolls lying in the same angular positions and all the odd numbered sets have the planes of revolution of their rolls in the same angular positions, the angular positions of the planes of revolution of the rolls in the even and odd numbered sets are displaced from one another. It follows, therefore, owing to the repeated passage of one and the same part of the tube through the region of the clearances between the flanks of one series of roll sets, either the even or the odd numbered, that irregular increases in the wall thickness of the tube will occur with the resulting formation of interior corners and ridges.

Now, the present invention relates to a method of reducing tubes by rolls and to reducing mills for carrying out the method whereby the aforesaid disadvantage is obviated.

According to the present invention the tubes on passing through the series of sets of two or more rolls are acted upon by the clearances between the flanks of the adjacent rolls of each set at continually changing places in its periphery. In this manner the effect produced by these clearances or spaces is distributed around the entire periphery of the tube and consequently the interior face of the wall of the tube remains truly circular.

The advantage intended by the present in-

vention can be obtained by imparting a rotary movement to the tube during its passage through the rolling mill for example by positioning the rolls obliquely or by rotating the tube by other means, for example by twisting guides.

Instead of this the planes of revolution of the reducing rolls in the successive sets of rolls may be so disposed that the clearances or spaces between the flanks of adjacent rolls constituting one of these sets occur at different angular positions in each set.

This can be effected in accordance with the invention in a particularly simple manner in universal rolling mills in which each set of rolls generally consists of more than two rolls and in which the shafts of each set of rolls are directly driven from a centrally arranged driving member, for example a hyperbolic gear wheel.

In the drawing, Figure 2 represents diagrammatically the usual arrangement for the sequence of the passes in which the individual passes are alternately displaced by 90°, and it shows a series of eight passes each of which is made up of two rolls.

Figure 3 illustrates diagrammatically by way of example an arrangement of similar rolls in accordance with the invention. In this case the passes are relatively displaced or staggered in such a manner that every part of the blank is acted upon only once by the clearances between the rolls on its passage through the series of rolls. If the passes are made up of more than two rolls, they also will be staggered in a similar manner.

Figure 4 illustrates by way of example the arrangement of obliquely positioned rolls which impart to the tube a rotary movement in addition to a longitudinal movement, each set of rolls being in this example constituted by two rolls only.

I claim:

In a tube rolling machine, a plurality of roll stands, each stand comprising opposed rollers having substantially semi-circular grooves therein, said roll stands being arranged in pairs disposed in a position with the diameter of the open portion of the groove of one roller of each pair disposed at a right angle to the diameter of the open portion of the groove of the other rollers of each pair, and the diameters of the open portion of the grooves of succeeding pairs of roll stands being arranged in progression with the diameter of the first member of each succeeding pair of roll stands arranged at an acute angle with respect to the diameter of the first member of a preceding pair of roll stands.

GUSTAV ASBECK.
